THOMAS P. MARSHALL, OF TRENTON, NEW JERSEY.

Letters Patent No. 72,656, dated December 24, 1867; antedated December 17, 1867.

STAMP-WETTING AND PEN-CLEANING INSTRUMENT.

The Schedule referred to in these Letters Patent and making part of the same.

TO ALL WHOM IT MAY CONCERN:

Be it known that I, THOMAS P. MARSHALL, of Trenton, New Jersey, have invented a Stamp-Wetting and Pen-Cleaning Instrument; and I do hereby declare the following to be a full, clear, and exact description of the same, reference being had to the accompanying drawing, and to the letters of reference marked thereon.

My invention consists of an instrument, fully described hereafter, for readily wetting the gummed surface of stamps, envelopes, or labels, and for cleaning and drying pens.

In order to enable others to make and use my invention, I will now proceed to describe its construction and operation, reference being had to the accompanying drawing, which forms a part of this specification, and in which—

Figure 1 represents an end view of my instrument for dampening stamps, envelopes, &c.

Figure 2 a front view, and

Figure 3 a sectional plan on line 1 2, fig. 2.

Similar letters refer to similar parts throughout the several views.

A and A' are the two side frames of the instrument, the latter being separated into upper and lower portions, a and b, by an opening, x, referred to hereafter. The frame A is connected to the upper portion a of the frame A' by a rod, e, and to the lower portion by the two rods f f, and between the frame A and the lower portion of the frame A' is held a trough, D, for containing water, in which a roller, h, and cylindrical sponge or wiper, m, are arranged to revolve, both roller and sponge being secured to a spindle, d, arranged to turn in the frames, in which also turns another spindle, d', carrying the roller h' and sponge m', similar to those below. Each spindle is furnished with a knob or other suitable handle, n, by the aid of which the spindle and its appurtenances may be revolved. The trough D is separated into two compartments by a partition, z, so that the water in which the sponge revolves cannot gain access to that in the compartment in which the cylinder h turns. In the present instance, the upper portions of the two frames have a series of projections, t, between which are recesses u, for holding pens, &c., but it should be understood that the form and construction of the frames may be altered without departing from the main features of the invention.

The rollers h and h' may be of wood or metal, without any covering, although I prefer to cover them with gum-elastic or other like material. The cylinders m and m' may be made of sponge, felt-cloth, plush, or other absorbent material, and may be corrugated, as shown in fig. 2.

In wetting a postage or other stamp, or gum label, it is held in one hand, gummed side downwards, and directed to the rollers, while one or other of the knobs n is held between the finger and thumb, and its spindle turned so that the stamp or label passes between the said rollers, and in doing this the gum is wetted by contact with the wet surface of the under roller. The opening x in the frame A' affords an opportunity for introducing the gummed flap of an envelope to, and passing it between, the two rollers in a manner which will be readily understood without description.

A clogged pen may be effectually cleansed by holding it in contact with the roller m, while the latter is being turned, the pen being subsequently dried by holding it to the surface of the upper and dry roller m', and turning the latter.

I claim as my invention, and desire to secure by Letters Patent—

1. The two rollers h and h', combined with a trough, D, substantially as described.
2. The rollers h and h' on spindles, caused to turn in a frame having an opening, x, through which an envelope or other article can be introduced to the said rollers, as set forth.
3. The said spindles d and d', each having a cylinder made of sponge, cloth, or other absorbent material, the cylinders being free from contact with each other, and the lower cylinder being arranged to revolve in a trough containing water, all substantially as set forth.

• In testimony whereof, I have signed my name to this specification in the presence of two subscribing witnesses:

Witnesses:

WM. HALL WAXLER,
W. J. R. DELANY.

THOMAS P. MARSHALL.
